by Wm. Belcher Atty.

UNITED STATES PATENT OFFICE.

PRIMIANO CASALENA, OF CHICAGO, ILLINOIS, ASSIGNOR OF ONE-HALF TO JOHN V. CANEPA, OF CHICAGO, ILLINOIS.

MACARONI-DRIER.

1,310,176.

Specification of Letters Patent. Patented July 15, 1919.

Application filed November 4, 1918. Serial No. 260,933.

To all whom it may concern:

Be it known that I, PRIMIANO CASALENA, a subject of the King of Italy, residing at Chicago, in the county of Cook and State 5 of Illinois, have invented certain new and useful Improvements in Macaroni-Driers, of which the following is a specification.

This invention relates to improvements in macaroni driers and more particularly to 10 the means for supporting the fan shaft to insure proper operation thereof.

The invention is designed, primarily, for use in connection with the macaroni drier disclosed in Letters Patent No. 1,285,615, 15 granted to John V. Canepa and myself on November 26, 1918, but it is not limited in its application to that particular drier.

The object of the invention is to provide an improved construction and arrangement 20 of the means for producing and disposing of the currents of air required for the drying operation and to support the fan shaft perpendicularly in a firm and rigid manner to prevent wabbling and insure proper operation 25 of the fan.

In the drawing,

Figure 1 shows the invention in section as applied to a drier constructed substantially in accordance with the patented drier above 30 referred to; and

Fig. 2 is a detail enlarged sectional view of one bearing.

Referring to the drawings, 1 is the drying chamber provided with an opening 2 in its 35 top and arranged within the shell 3. Deflectors 4 are located below the top of the shell and above the opening 2 and these deflectors terminate at the doors 5 which are adapted to be opened to permit escape of air 40 currents induced by the fan 6 which is suspended in horizontal position in the opening 2. The lower edges of the deflectors meet in a line diametrically above the opening in the chamber.

45 It is customary to build these driers in a so-called loft or a room in the factory where macaroni, spaghetti and other paste products are produced and in the drawing 7 indicates the beams of the ceiling of such a 50 room. The fan shaft 8 is supported in three bearings of substantially the same construction, one located at the ceiling of the room, one at the top of the shell and one adjacent

the fan, and the driving pulley 9 is mounted on the shaft between the ceiling and the top 55 of the shell.

The upper bearing comprises a lower member 10 bored to receive the shaft and having lateral projections 11 to receive bolts 12 which secure said member to a cross 60 piece 13 fastened to the underside of two adjacent ceiling beams 7. This lower member is provided with an outer peripheral flange 14 and an inner peripheral flange 15 with an annular intervening space 16. 65

The upper member 17 has an elongated upwardly extending integral sleeve 18 and is adapted to be fastened to the shaft by a set screw 19. This upper member has a depending outer peripheral flange 20 which 70 surrounds the lower member, an outer peripheral groove 21 to receive the outer peripheral flange 14 of the lower member and an inner peripheral recess 22 to receive the inner peripheral flange 15 of the lower member. 75 The intermediate annular portion 23 of the upper member between the groove 21 and the recess 22 projects into the annular space 16 of the lower member and is spaced from the lower member by the bearing balls 80 24 which are seated in grooves provided therefor in the upper and lower members. Grease is packed in the space 16 to keep the balls constantly lubricated.

The intermediate bearing 25 is made like 85 the upper bearing, just described, the lower member being turned so that the projections 11 thereon will extend lengthwise of the beam 26 upon which this bearing is mounted and to which it is suitably secured. The 90 lower bearing 27 is substantially like the upper and intermediate bearings and it is supported in place by braces 28 fastened to the projections on the lower member and to the top of the shell 3, these braces being 95 preferably provided with turn-buckles 29 whereby they may be conveniently maintained taut.

The hub 30 of the fan is secured by a set 100 screw 31 on the shaft and between this hub and the lower bearing I provide a collar 32 which is secured on the shaft by set screw 33. A ball bearing of any suitable character is located between the collar 32 and the lower member of the lower bearing.

I may also provide a headed bolt 35 on

the lower end of the shaft to assist in securing the fan in place and a collar 36 and set screw 37 at the upper end of the shaft.

My invention is simple in construction 5 and it can be easily applied. In practical use I have found that it will securely hold the fan shaft in perpendicular position without binding at any of the bearings and will prevent the fan from wabbling at any required speed of revolution.

I am aware that changes in the form and proportion of parts and in the details of construction of my invention may be made without departing from the spirit or sacrificing any of the advantages thereof and I 15 reserve the right to make all such changes as fairly fall within the scope of the appended claims.

I claim:

20 1. In a macaroni drier, the combination of a drying chamber having an opening in the top thereof, a shell inclosing said chamber and having its top spaced from the top of the chamber, a fan arranged horizontally 25 in said opening, a perpendicular shaft for said fan extending up through the top of the shell, two bearings for said shaft located within the shell, one adjacent the fan and the other adjacent the top of the shell, and 30 a bearing for the upper end of the shaft.

2. In a macaroni drier, the combination of a drying chamber having an opening in the top thereof, a shell inclosing said chamber and having its top spaced from the top 35 of the chamber, a fan arranged horizontally in said opening, a cross-beam located within the shell above the opening in the chamber, a perpendicular shaft for said fan extending up through the beam and the top 40 of the shell, a bearing for the shaft adjacent the fan, another bearing for the shaft located on the beam, and another bearing for the upper end of the shaft.

3. In a macaroni drier, the combination 45 of a drying chamber having an opening in the top thereof, a shell inclosing said chamber

and having its top spaced from the top of the chamber and provided with doors therein, deflectors extending from the doors inwardly and downwardly to a meeting line 50 diametrically above said opening, a fan arranged horizontally in said opening, a perpendicular shaft for said fan extending up between the deflectors and through the top of the shell, a bearing for the shaft adjacent the fan, another bearing for the shaft located between said deflectors, and another bearing for the shaft at the upper end thereof.

4. In a macaroni drier, the combination 60 of a drying chamber having an opening in the top thereof, a shell inclosing said chamber and having its top spaced from the top of the chamber, there being doors in the top of said shell, deflectors located between the 65 doors and extending therefrom downwardly to a meeting line diametrically disposed above said opening, a beam extending across the shell between said deflectors, a fan arranged horizontally in said opening, a perpendicular shaft for said fan extending up between the deflectors and through the beam and the top of the shell, a bearing for the shaft adjacent the fan, another bearing for the shaft located on the beam beneath the 70 top of the shell, and another bearing for the top of the shell, and another bearing for the upper end of the shaft.

5. In a macaroni drier, the combination 75 of a fan shaft and a bearing therefor comprising a lower member and an upper member, the upper member having a peripheral flange to surround the lower member, a peripheral groove and a peripheral recess, and the lower member having peripheral flanges to engage the groove and recess of the upper member, and balls located between the two members in the annular space between the flanges of the lower member.

PRIMIANO CASALENA.
